ODORIZER FOR NATURAL GAS LINES

John T. Rutherford, Berkeley, and William E. Stock, Jr., Richmond, Calif., assignors to Standard Oil Company of California, San Francisco, Calif., a corporation of Delaware

Application February 13, 1940, Serial No. 318,724

6 Claims. (Cl. 48—195)

This invention relates to devices for introducing a volatile liquid having a distinctive odor into a stream of natural gas flowing in a line, and particularly refers to one of the by-pass type which utilizes a combination of surface evaporation and atomization to secure substantially constant and complete saturation of that portion of the gas passing through the device, at widely varying gas flow rates.

Generally, a by-pass type odorizer is one in which a proportional part of the gas passing through a flow restriction, such as a valve or orifice plate in a main line, is diverted or by-passed through pressure connections, suitably spaced from the flow restriction, into and through a chamber in which a volatile liquid is exposed to be evaporated. The pressure differential set up by the flow restriction constitutes the driving force to by-pass the gas into the chamber and to return it again to the main gas stream. Desirably the by-passed gas is substantially completely saturated with the volatile liquid, and the degree of odorization of the total gas flow, usually expressed in gallons per million cubic feet, is controlled by the size of the orifice or the degree of opening of the valve which comprises the flow restriction in the main line.

The flow rate in many natural gas lines varies through very wide ranges, and this is particularly true in those numerous scattered installations of small throughput to which the present invention is particularly adapted. Accordingly, two types of evaporation promoting and controlling means are employed in combination, one adapted to saturate the by-passed gas at very low flow rates, and the other adapted to cooperate with and supplement the first when the gas flow increases, this action being entirely automatic and not employing external forces or moving parts other than the gas and liquid which are being handled.

Heretofore most by-pass odorizers utilized deflected gas streams which increased turbulence to enhance vaporization of the odorant liquid. Other types have used wicks of capillary material to increase wetted surface area. In those designs the degree of saturation of the gas with odorant liquid was largely a function of the flow rate, at low rates a greater degree of saturation being obtained but decreasing rapidly with increasing flow rates. Thus the saturation, and hence odorant evaporation, would vary with gas flow rate. In certain designs an attempt was made to obtain saturation at all times by submerging the gas inlet and forcing the gas to bubble through a depth of liquid. Such an ar-

angement obviously could not provide odorization at main line gas flow rates below those which would create a pressure differential equal to the static head of the liquid, and true proportioning could not be obtained at higher flow rates because of the added static pressure on the by-passed gas, which added a constant value to the proportional pressure differential caused by the flow restriction in the gas line.

This invention comprehends broadly a chamber for odorant liquid, a gas inlet for the chamber directing the incoming gas through a predetermined path above the liquid level and in contact with a wetted wick or extended capillary surface, and means cooperating with the gas inlet and only effective at higher gas flow rates to atomize the odorant liquid into the by-passed gas stream, thereby giving substantially complete saturation of the latter under flow conditions that are of such magnitude that the evaporative capacity of wick or extended capillary surface would be inadequate. In order to insure that the composition of the odorant liquid remains substantially constant over long periods of use so that evaporation from an equilibrium mixture is obtained, it is desirable to regulate the liquid level range within limits and also to provide either an appreciable volume of odorant liquid in the evaporating chamber, so that additions of fresh, unweathered liquid will not unduly affect its vapor pressure and volatility, or to provide a separate odorant storage reservoir and a liquid level control means that will continuously replenish the odorant in the evaporating chamber as it is volatilized into the gas.

It is an object of this invention to provide a simple and automatically acting evaporative type gas odorizer that will give substantially complete saturation of gas by-passed from a main line for wider variations of flow in the latter than has heretofore been possible.

Another object is to provide a by-pass type odorizer that will give more truly proportional feed of odorant with respect to gas volume than in those heretofore known.

Another object is to provide an odorizer in which there are no moving parts and small ports or passages to clog, and which is so economical to fabricate, install and maintain that its use may be extended to locations where odorization has not been feasible.

These and other objects and advantages will be further apparent from the following description and from the attached drawing, which forms a part of this specification and illustrates

a preferred embodiment of the invention as well as an alternative form which has been found to be desirable.

In the drawing, Figure 1 is a vertical sectional view of an odorizer connected to a typical gas line and illustrates a preferred form of evaporating and atomizing means for the odorant liquid.

Figure 2 is a vertical sectional view of an alternative form of odorizer embodying this invention and arranged to maintain a constant liquid level in the evaporating chamber.

Figure 3 is a vertical sectional view of one form of gas inlet and odorant atomizer for the apparatus of Figures 1 and 2.

Referring to the drawing and particularly to Figure 1, reference numeral 10 designates a pipe line through which natural gas is flowing in the direction indicated by the arrow. A flow restriction means, which may be a valve or, in this case, an orifice plate 11, is placed in line 10 to create a pressure differential therein in the well known manner. Valved pressure connections 12 and 13 constitute, respectively, the high pressure and reduced pressure connections to the evaporating chamber and odorant reservoir 14. Preferably the chamber 14 is buried in the earth 15, insulated, or otherwise arranged to be at a substantially constant temperature independent of atmospheric temperature changes. Also, the evaporating chamber is preferably arranged horizontally so that changes in odorant quantity therein will modify the liquid level as little as possible. This is particularly true in the embodiment of Figure 1, where the liquid level falls as the odorant is evaporated from chamber 14.

In this example, chamber 14 comprises a cylindrical shell 16 closed at one end and provided with a removable closure such as a bolted plate 17 at the other end. A straight pipe 18 extends to the surface of the earth for gauging the level of the odorant 19 in the chamber and for replenishing the same, and is normally closed by a valve 20. A suitable valved drain 21 is provided to empty chamber 14 when required.

The high pressure connection 12 from pipe 10 forms the gas inlet to chamber 14, extending into the chamber a short distance from the inner face of plate 17, above the liquid level of odorant 19 and terminating in a Venturi type aspirating nozzle generally designated 22. One form suitable for nozzle 22 is shown in Figure 3, and, in that example, consists of a body 23 threaded onto pipe connection 12, said body having a constricted throat or bore 24, with a side passage 25 terminating therein. A conduit 26 leads downwardly from passage 25 to a point below the liquid level in chamber 14. The discharge end of bore 24 is enlarged at 27 in the usual manner, so that gas passing into chamber 14 from the high pressure connection 12 when the main gas stream in line 10 is flowing at high rates, will aspirate odorant liquid through conduit 26 and will atomize it into the chamber, increasing the evaporation rate to maintain the by-passed gas substantially saturated with the odorant.

Extending into chamber 14 from the inside face of plate 17 and surrounding the gas inlet nozzle 22 is an absorbent extended capillary surface, in this case a helically wound or woven cotton wick 28, desirably supported by fluid-permeable means such as a perforated metal tube 29, and with its lower portion below the level of odorant 19 so as to be wetted thereby. The

gas outlet 36 from chamber 14 may also extend through closure plate 17 at a point above the liquid level of the odorant 19, and communicates with the gas main 10 through the reduced pressure connection 13. At low gas flow rates in main 10, which would not cause a high enough pressure drop across restriction 11 to actuate the nozzle 22 to inspirate and atomize the odorant, the by-passed gas passing outwardly from nozzle 22 and flowing over the wetted surfaces of wick 28 will be found to evaporate sufficient odorant to be substantially completely saturated. Thus a fully automatic means have been provided to by-pass gas from a main at a rate proportional to the flow of gas therein, the by-passed gas moving into and through an odorant evaporating chamber where it is substantially saturated by simple evaporation at low gas flow rates and by a combination of such evaporation and liquid atomization at high gas flow rates, the gas then being returned to the main where it imparts a distinctive odor at a controlled and predetermined rate to the main gas stream. At the high gas flow rates, the mist or fog from the nozzle 22 will also wet the capillary material 28 above the liquid level, thereby insuring that no part of it will be dried out and rendered ineffective.

The arrangement of Figure 2 is similar in most respects to that just described, the principal difference being that the odorant liquid 19 in chamber 14 is maintained at a substantially constant level A and, as it is evaporated, is replenished from a storage reservoir 30 through a strainer 31 and a liquid level controller 32, the vapor space of the latter being connected in the usual manner to the vapor space of the reservoir 30 by a pressure equalizing line 33. In that example the perforated tube support 29 for wick 28 is preferably arranged to be substantially concentric with the small diameter shell 34 and spaced therein by lugs 35. In the arrangement of Figure 1, the liquid level preferably should be maintained in the range B, which should represent not over about 25% of the total liquid volume of odorant charge, particularly where the latter is a mixture of components having different degrees of volatility, so that approximate equilibrium vaporization will be obtained.

An example of an apparatus constructed according to this disclosure maintained substantially complete saturation in the by-passed gas at flow rates through the device ranging from about 40 to 450 cubic feet per hour, the pressure differential to cause such flow ranging from 1 to 130 inches of water. At differentials below about 2 inches of water the Venturi nozzle did not atomize and purely evaporative operation resulted without affecting the proportioning of the liquid odorant to the natural gas.

Although specific constructions have been described and illustrated, it is to be understood that many changes and modifications can be made without departing from the invention, and all such alterations that fall within the scope of the appended claims are embraced thereby.

We claim:

1. A by-pass type odorizer for natural gas lines, comprising a chamber for odorant liquid, means in said chamber forming an extended capillary surface to be wetted by said odorant, a gas inlet for said chamber above the level of liquid therein and adjacent said capillary means to direct gas therover and to evaporate said odorant liquid therefrom, a gas outlet above the liquid level in

said chamber, and an aspirating nozzle for said gas inlet to atomize odorant liquid into said gas and onto said extended capillary surface above the liquid level to wet the same with odorant liquid at high flow rates through said chamber.

2. An odorizer according to claim 1, in which the means forming said extended capillary surface comprises a generally hollow cylinder of absorbent material surrounding said gas inlet and defining the passage of gas through said chamber.

3. An odorizer according to claim 1, in which the means forming said extended capillary surface comprises a generally hollow cylinder of absorbent material surrounding said gas inlet, and means for supporting said cylinder in contact with said liquid substantially throughout its length.

4. An odorizer according to claim 1, with the addition of means for maintaining a predetermined liquid level range in said chamber.

5. An odorizer according to claim 1, in which said chamber comprises a horizontal cylinder closed at both ends and the means forming said

extended capillary surface comprises a hollow cylinder extending parallel to and substantially throughout the length of said chamber.

6. A by-pass type odorizer for natural gas lines comprising a horizontal chamber for odorant liquid, said chamber being closed at one end, removable closure means for the opposite end of said chamber, a gas inlet for said chamber carried by said closure means, a liquid permeable support means carried by said closure means to surround said gas inlet and to project into said chamber, an absorbent material supported by said last-named means to be wetted by odorant liquid in said chamber, a portion of said absorbent material extending above the level of liquid in said chamber, a gas outlet for said chamber above the liquid level therein, and means controlled by the passage of gas through said inlet for atomizing odorant liquid into said gas stream and onto said absorbent material above the liquid level to wet the same with odorant material at high gas flow rates.
